CLAIM

The ornamental design for a carousel for holding coffee pods, as shown and described.

DESCRIPTION

FIG. 1 is a top, front and left side perspective view of a carousel for holding coffee pods showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines shown in the figures depict portions of the carousel for holding coffee pods that form no part of the claimed design.

1 Claim, 7 Drawing Sheets
